UNITED STATES PATENT OFFICE.

HENRY G. VOIGHT, OF NEW BRITAIN, CONNECTICUT.

FIRE-DOOR LOCK.

1,070,365.

Specification of Letters Patent. Patented Aug. 12, 1913.

Application filed January 31, 1913. Serial No. 745,386.

To all whom it may concern:

Be it known that I, HENRY G. VOIGHT, a citizen of the United States, residing at New Britain, Hartford county, State of Connecticut, have invented certain new and useful Improvements in Fire-Door Locks, of which the following is a full, clear, and exact description.

This invention relates to so-called "fire door" locks and more particularly to the general type of fire door lock disclosed in my prior Patent No. 1,047,900 of December 17th, 1912, in which a plurality of spaced gravity locking bolts are employed, these bolts being retractable through a common operating means and being blocked against surreptitious retraction independently of said operating means, mechanism being provided in addition for automatically locking 20 these bolts retracted upon the opening of the door and for automatically releasing said bolts upon the closing of the door.

The present invention embodies a "fire door" lock of this general character providing improved bolt operating and blocking means, a detailed description of which will be found in the following specification taken in connection with the accompanying drawings forming part thereof, and illustrating a preferable embodiment of my improved form of lock.

In these drawings, Figure 1 is a view in elevation of the lock frame and the assembled lock parts, the face or wall of the hollow metal door and a plate of the lock case being removed to disclose the interior arrangement. Fig. 2 is a vertical section through the door with the lock frame and lock in position therein. Fig. 3 is a fragmentary vertical section, on an enlarged scale, taken through the lower end of the door. Fig. 4 is a similar section through the upper end of the door. Fig. 5 is a view of a detail. Fig. 6 is a fragmentary view in elevation of the upper end of the lock frame and its parts, and illustrates a modified form of lock.

As a preface to a description of the elements of the drawings, I may state that the lock of the present invention is of the type intended for application as a unitary structure to hollow metal doors, the frame being insertible within the door from its edge, the outer face of the frame forming the edge plate of the door.

Referring now to the structure shown in

the drawings: The lock frame proper is preferably in the form of an angle iron comprising the side bars 1 and 2, which bars may be readily shaped to provide the proper bevel for the edge of the door. This angle iron extends substantially the entire height of the door and at suitable intervals, longitudinally thereof, studs 3 are provided, these studs being intended for spot welding to the inner face of the hollow door. The bar 1 of the angle iron has an offset portion 4 (Fig. 1) to which a lock casing is appropriately secured, this casing comprising plates 5 spaced apart and secured in such relation by studs 6. The sleeve 7 of an operating handle (not shown) is carried within this lock case, the spindle (not shown) from said handle seating in the hub 8 of the roll back 9. Seated over this roll back 9 and its hub 75 and supported thereby is a yoke 10 having one end rigidly secured to an operating bar 11 extending longitudinally of the lock frame. This operating bar is mounted to have a combined longitudinal and transverse motion. Adjacent its lower end a bracket 12 projects from the bar 2 of the angle iron and a link 13 is pivotally connected to this bracket and to the lower end of the bar. Adjacent the upper end of the 80 angle iron, its bar 2 has secured thereto and projecting therefrom a bracket plate 14, this plate being provided with an elongated aperture 15 therein through which the operating bar 11 extends and by means of which the combined longitudinal and transverse movement of the bar is permitted.

At a plurality of points longitudinally of the angle iron, the bar 1 of the angle iron is provided with pivot studs 16 on each of 95 which a locking bolt 17 is journaled by means of a pin 18. Each bolt is formed with a cam slot 19 therein adjacent its rear end, co-operating with which are studs 20 carried by and projecting from the operating bar, one stud being provided for each bolt. The studs are seated within the cam slots and lie at the rear ends of said slots when the bolts are projected. The bar 2 of the angle iron may be provided with a suitable finish plate 21, both this plate and the bar 2 being suitably apertured to permit the projection and retraction of the locking bolts 17.

To the upper end of the operating bar 11 110 is pivotally secured a locking head 22 having a locking recess 23 therein. A trans-

versely extending plate 25 is suitably secured to the bar 2 of the angle arm at its upper end, and to this plate is secured an abutment bracket 24 which projects downwardly from said plate and terminates at a point immediately above the upper end of the operating bar 11 and of the side of the locking head 22 when the bar and its locking head are dropped into bolt projected position (see Figs. 1 and 2). Adjacent the bracket 24, the plate 25 carries spaced ears 26 between which a locking dog 27 is pivotally mounted, the upper end of this locking dog extending through suitable apertures formed in the plate and said dog being provided with a lateral offset 28 designed to coöperate with the locking recess 23 of the locking head 22 of the operating bar, as will be more clearly seen later.

With the foregoing structure in mind, it will be seen that the operation of the lock is as follows: Assuming that the door is closed with the bolt 17 projected into suitable recesses formed in the strike plate of the door jamb, and assuming that it is desired to open the door from the interior. The roll back 9 is oscillated through the medium of the operating handle on the interior of the door, thus raising the yoke 10 and swinging the operating bar 11 diagonally outward, this diagonal movement of the bar being permitted by reason of the connections heretofore described. The studs 20 of the operating bar will ride in the cam slots 19 of the locking bolts, and by reason of the curvature of said slots, will swing the projecting head of said bolts inwardly and retract the same. This diagonally outward movement of the bar will also swing its locking head 22 clear of the stop or abutment 24, the side of the locking head contacting with the edge of said abutment and swinging the locking head upwardly to a vertical position, as shown in Fig. 4.

The upper face of the door jamb at the point where the projecting head of the locking dog 27 contacts therewith, is flush and without a recess within which this head may project. When the door is closed, therefore, the head of the dog 27 is moved inwardly, swinging the offset 28 out of the path of the locking head 22 of the operating bar. When the door is opened, however, by the means just described, the head of the locking dog 27 is released and it swings in by gravity to bring its offset 28 within the locking recess 23 within the head 22 of the operating bar, thereby serving to hold the operating bar in its raised position, and at the same time, holding the locking bolts 17 retracted. When the door closes, the head of the locking dog contacts with the upper face of the door jamb and is thrown inwardly, swinging its offset 28 out of the recess 23 of the head 22 and permitting the

operating bar 11 to drop by gravity, this movement of the bar through its studs 20 serving to move the locking bolts 17 outwardly into locking position. On this downward movement, by reason of the manner in which the operating bar 11 is mounted and by reason of the curvature of the cam slots of the locking bolts, the bar 11 swings downwardly and inwardly, its head 22 swinging outwardly and clearing the under face of the abutment 24, the parts assuming the position shown in Fig. 1.

By reason of the provision of the abutment bracket 24, the bolts are locked against retraction independently of the operating bar 11, as by the insertion of a knife blade or other implement between the door edge and jamb. Such an attempt to surreptitiously retract the bolts will merely serve to move the operating bar slightly upward to bring its head 22 against the under face of the bracket 24, which blocks further movement of the operating bar and absolutely prevents retraction of the bolts through such medium.

In Fig. 6 I have shown a modified form of locking bolt adapted to block retraction independently of the operating bar without using such an abutment bracket. In this modification, the pivoted locking bolts 29 are provided with curved cam slots 30 therein, these cam slots having their outer edge formed with a shouldered portion 31. The operating bar is guided in one or more brackets 32 having apertures 33 therein of somewhat greater diameter than the operating bar so that this bar may move freely therethrough in a vertical direction. The bar will, of course, have the yoke and roll back attachments heretofore described in connection with the first form of lock, the yoke resting on the roll back and supporting the operating bar. As this bar moves freely through its guiding bracket or brackets 32, it is, of course movable slightly in a transverse direction. The locking bolts 29 cannot be retracted independently of the operating bar, as by the insertion of a knife blade between a bolt and the door jamb. Such retraction will cause the shouldered portion 31 of the cam slot to press against the coöperating stud of the locking bar and in turn move said bar laterally to a slight extent, frictionally binding it against the slotted edge of its brackets 32 which, therefore, act as abutments to block the retraction of the bolts. The bolts may be retracted, however, through the operating handle which causes a vertical movement of the operating bar, the stud of the operating bar coöperating with each bolt member riding up over the uninterrupted curved edge of the cam slot and freely swinging the bolt inwardly. The operating bar is provided with a fixed locking head 34 having a locking recess 35 there-

in which coöperates with the offset locking flange 36 of the pivoted locking dog 37, as heretofore described in connection with the other form of locking head and dog. In 5 this form of my device, as in the one first described, there is, therefore, movement of the operating bar in two different directions, one direction of movement being through the operating handle and being adapted to 10 retract the bolts and the other direction of movement of said bar blocking its operation to retract said bolts, this last action taking place upon attempted retraction of the bolts independently of the operating bar (as 15 through a knife inserted between the door and jamb as heretofore suggested).

While I have herein described specific structural embodiments of my invention, it will be understood that the same may be 20 modified in detail and relative arrangement of parts within the spirit of the invention and the scope of the appended claims.

What I claim, therefore, and desire to secure by Letters Patent is:

25 1. In a lock of the character described, in combination, a plurality of spaced latch bolts, a common operating member therefor movable in two different directions, manually operable means for moving said member in one direction to retract said bolts, means whereby attempted retraction of said bolts independently of said operating member moves said member in another direction, and means blocking the operation of said 35 member to retract said bolts upon such movement.

2. In a lock of the character described, in combination, a plurality of spaced latch bolts, means normally tending to project said 40 bolts, a common operating member therefor movable in two different directions, manually operable means for moving said member in one direction to retract said bolts, means whereby attempted retraction of said 45 bolts independently of said operating member moves said member in another direction, and means blocking the operation of said member to retract said bolts upon such movement.

50 3. In a lock of the character described, in combination, a plurality of spaced latch bolts, a common operating member therefor movable in two different directions, manually operable means for moving said member in one direction to retract said bolts, means whereby attempted retraction of said 55 bolts by moving the same inwardly from the door jamb independently of said operating member moves said member in another direction, and means blocking the operation of said member to retract said bolts upon such movement.

4. In a lock of the character described, in combination, a plurality of spaced latch 60 bolts, means normally tending to project said

bolts, a common operating member therefor movable in two different directions, manually operable means for moving said member in one direction to retract said bolts, means whereby attempted retraction of said 70 bolts independently of said operating member moves said member in another direction, means blocking the operation of said member to retract said bolts upon such movement, means for retaining said latch bolts in retracted position after the door has been 75 opened, and for releasing said bolts when the door is closed whereby they may be projected.

5. In a lock of the character described, in combination, a plurality of spaced latch bolts, a common operating member therefor movable in two different directions, an abutment positioned in the path of said member in one direction of movement thereof and adapted to block bolt-retracting movement of said member, manually operable means for moving said operating member in a direction to retract said bolts, and means whereby attempted retraction of said 80 bolts independently of said operating member moves said member in a direction to engage said abutment whereby retraction of said 85 bolts is blocked.

6. In a lock of the character described, in combination, a plurality of spaced latch bolts, means normally tending to project said bolts, a common operating member therefor movable in two different directions, an abutment positioned in the path of said member in one direction of movement thereof and adapted to block bolt-retracting movement of said member, manually operable means for moving said operating member in a direction to retract said bolts, 90 means automatically operable upon the opening of the door to retain said latch bolts in retracted position, and automatically releasing said bolts upon the closing of the door whereby they may be projected, and means whereby attempted retraction of said 95 bolts independently of said operating member moves said member in a direction to engage said blocking abutment.

7. In a lock of the character described, in combination, a plurality of spaced pivoted latch bolts having cam slots therein, a common operating bar therefor movable in two different directions, said bar being provided with a plurality of actuating studs engaging 100 in said cam slots and being normally positioned by gravity to project said bolts, an abutment positioned in the path of said operating bar in one direction of movement thereof and adapted to block bolt-retracting movement of said bar, manually operable means for moving said bar in a direction out of line with said abutment to retract said 105 bolts, and means whereby attempted retraction of said bolts independently of said operating 110 member moves said member in a direction to engage said blocking abutment.

115 8. In a lock of the character described, in combination, a plurality of spaced pivoted latch bolts having cam slots therein, a common operating bar therefor movable in two different directions, said bar being provided with a plurality of actuating studs engaging 120 in said cam slots and being normally positioned by gravity to project said bolts, an abutment positioned in the path of said operating bar in one direction of movement thereof and adapted to block bolt-retracting movement of said bar, manually operable means for moving said bar in a direction out of line with said abutment to retract said 125 bolts, and means whereby attempted retraction of said bolts independently of said operating member moves said member in a direction to engage said blocking abutment.

130

erating bar moves said bar in a direction to engage said abutment whereby retraction of said bolts is blocked.

8. In a lock of the character described, in combination, a plurality of spaced pivoted latch bolts having cam slots therein, a common operating bar therefor movable in two different directions, said bar being provided with a plurality of actuating studs 5 engaging in said cam slots and being normally positioned by gravity to project said bolts, an abutment positioned in the path of said operating bar in one direction of movement thereof and adapted to block bolt-retracting movement of said bar, manually operable means for moving said bar in a direction out of line with said abutment to retract said bolts, a locking head carried by said bar operatively positioned by bolt-retracting 10 movement thereof, a movable latching member automatically positioned by the opening of the door to engage said locking head and retain said bolts in retracted position, and automatically moved by the closing of the 15 door to disengage said locking head whereby said bolts may be projected, and means whereby attempted retraction of said bolts independently of said operating bar moves said bar in a direction to engage said abutment whereby retraction of said bolts is blocked.

9. A unit lock of the character described, comprising, in combination, a frame, a plurality of spaced bolts carried thereby, a common operating member for said bolts mounted in said frame for movement in two different directions and normally tending to move said bolts into projected position, manually operable means carried by said frame 35 for moving said member in one direction to retract said bolts, means whereby attempted retraction of said bolts independently of said operating member moves said member in another direction, and means 40 blocking the operation of said member to retract said bolts upon such movement in another direction.

10. A unit lock of the character described, comprising, in combination, a lock frame, a plurality of spaced latch bolts carried thereby, a common operating member for said 45

bolts in operative connection therewith and mounted in said frame for movement in two different directions, said operating member normally tending to move said bolts to projected position, an abutment carried by said frame and positioned in the path of said member in one direction of movement thereof, said abutment being adapted to block bolt-retracting movement of said member, 60 manually operable means for moving said operating member in a direction out of the path of said abutment to thereby retract said bolts, and means whereby attempted retraction of said bolts independently of said operating member moves said member in a direction to engage said abutment whereby retraction of said bolts is blocked.

11. A unit lock of the character described, comprising, in combination, a lock frame, a plurality of spaced latch bolts carried thereby, a common operating member for said bolts in operative connection therewith and mounted in said frame for movement in two different directions, said operating member 70 normally tending to move said bolts to projected position, an abutment carried by said frame and positioned in the path of said member in one direction of movement thereof, said abutment being adapted to block bolt-retracting movement of said member, 75 manually operable means for moving said operating member in a direction out of the path of said abutment to thereby retract said bolts, a locking head carried by said member 80 operatively positioned by bolt-retracting movement thereof, a movable latching member automatically positioned by the opening of the door to engage said locking head and retain said bolts in retracted position, and automatically moved by the closing of the 85 door to disengage said locking head whereby said bolts may be projected, and means whereby attempted retraction of said bolts independently of said operating member 90 moves said member in a direction to engage said abutment whereby retraction of said bolts is blocked.

HENRY G. VOIGHT.
